UNITED STATES PATENT OFFICE.

VICTOR G. BLOEDE, OF BALTIMORE, MARYLAND, ASSIGNOR OF ONE-HALF
TO JOHN BANCROFT, OF WILMINGTON, DELAWARE.

PROCESS OF DYEING.

SPECIFICATION forming part of Letters Patent No. 394,447, dated December 11, 1888.

Application filed January 18, 1888. Serial No. 261,148. (No specimens.)

To all whom it may concern:

Be it known that I, VICTOR G. BLOEDE, a citizen of the United States, and a resident of the city of Baltimore, in the State of Maryland, have invented certain new and useful Improvements in Processes of Coloring or Tinting Fabrics, of which the following is a full and exact specification.

My invention relates to processes for tinting or coloring fabrics, such as are used for window-shades, book-cloths, furniture-coverings, and linings for clothing. The goods now used for these and similar purposes are generally prepared by the ordinary dye processes, which are always more or less expensive and with which it is almost impossible to produce fastness against light, and window-shades and book-cloths are sometimes prepared by painting the surface with mineral color, in which case the goods are made thick and heavy and are easily broken or otherwise destroyed. Then, too, the color is always affected by perspiration and the goods discolored. By my method I can produce goods which will have the character of either of these classes—the first, in which the fabric is tinted, so as to render the goods soft and pliable, and, the second, in which a stiff-filled goods is required. My method gives an advantage over the first class in that my process is cheap, and I am enabled with it to use color—such as carbon—which is entirely fast against light, and also that will be unaffected by perspiration, and in the second class my goods are smoother than painted goods, cheaper, and more pliable without breaking or dislodging the color, and also possess the same qualities as my goods of the first class. To produce goods resembling dyed goods and capable of resisting washing, I take as a base a more or less liquid soap—any form of fatty matter rendered soluble in water by any of the well-known processes.

Having selected my base, which, as stated, may be fatty matter rendered soluble in water by any of the known processes, I incorporate with it any suitable pigment or color in sufficient quantity to insure the shade required. The mixture is then generally ground in a mill to the finest and most thorough combination, although some colors mingle sufficiently well without any grinding. The mixture of water, soluble fatty matter, and

color constitutes the first step of my process. Having made the mixture to suit the shade wanted, the coloring-mixture is applied to the fiber or fabric in any convenient manner. It may be applied as a paint by means of brushes, or the goods may be immersed in or run through the coloring-mixture. The fiber or fabric having been thoroughly impregnated by any of these methods, and the surplus of color having been thoroughly removed by pressure or otherwise, the goods are now subjected to the second process. In most cases I find it desirable before proceeding to the second treatment to dry the goods; but this is not an essential feature, as I can produce good results by treating the goods still damp from the process of impregnation.

The second step of my process consists in passing the goods evenly impregnated with the soluble fatty matter and color through a bath of any substance having the power to convert the hitherto soluble fatty matter into an insoluble compound, thus firmly binding the color to the fiber by means of the elastic insoluble matter thereby produced. I have found chloride of calcium, owing to its low cost as well as inherent properties, to answer my purpose best, but do not confine myself to it, as chloride of magnesium, salts of zinc, and many other substances can be made to answer nearly as well—in fact, any salt of the earth or metals possessing the power of converting the soluble fatty matter into an insoluble compound. The goods, after having been acted upon in the manner described, are then washed, dried, and finished in any manner desired.

Instead of using a mixture of soluble fatty matter alone, starch or gum may be added to the coloring compound, in order to give it more body or consistency.

To produce goods the interstices and surface of which are covered, I make a mixture of soluble fatty matter, pigment, or color, (with or without the addition of starch or gum,) as before, only the consistency of the compound is increased to the extent that when suitably mixed or incorporated the material possesses the consistency of putty or bread-dough. For this process I prefer to use the soda saponifications, owing to the fact that they possess a much greater consistency than the correspond-

ing potash or sulpho-oleate compounds. Whenever desirable for the production of greater body or covering power, clay, baryta, or other earthy matter may also be added to 5 the mixture.

Having prepared the compound of proper consistency and color, the application of it to the fiber or fabric is made by means of a spreading-machine or Scotch mangle in the 10 manner well known to the art for the application of size, &c., to fabrics. One or more coatings having been given to the material, the goods are (properly, but not necessarily) dried and are then taken through a chemical 15 bath, as previously described, having for its object the conversion of the soluble fatty matter into the insoluble modification.

As stated, I do not in the above process confine myself to any particular kind of soluble 20 fatty matter, as any soluble fatty matter capable of being carried over into an insoluble form is more or less well adapted for my use. Neither do I confine myself to the chloride of calcium in producing this conversion, having 25 found many other substances of service.

What I claim as my invention is—

1. The method herein described of coloring or tinting fabrics, which consists of applying to or impregnating the fabric with a mixture 30 of soluble fatty matter and coloring-matter, and then rendering the fatty matter insoluble by treating the fabric thus impregnated with chloride of calcium or other equivalent compounds having the power of rendering fatty 35 matter insoluble, substantially as described.

2. The process above described of coloring or tinting fabrics, which consists of first applying to or impregnating the fabric with a mixture of soluble fatty matter—such as pot-

ash soap—and gum, or starch, or glue, and coloring-matter, and then rendering the fatty matter insoluble by treating the fabric thus impregnated with chloride of calcium or other equivalent compound having the power of rendering the fatty matter insoluble, substantially as described. 40

3. The process above described of coloring fabrics, which consists of applying by friction, pressure, or otherwise to the surface of the fabric a mixture of soluble fatty matter—such as soda soap—and coloring-matter, and then treating the fabric with chloride of calcium or the equivalent compound having the power of rendering the soluble fatty matter insoluble, substantially as described. 45

4. The above-described process of coloring fabrics, which consists of applying by friction, pressure, or otherwise to the surface of a fabric a mixture of soluble fatty matter—such as soda soap—clay, and coloring-matter, and then treating the fabric with chloride of calcium or other equivalent compound having the power of rendering the soluble fatty matter insoluble, substantially as described. 50

5. The above-described process of coloring fabrics, which consists of applying by friction, pressure, or otherwise to the surface of a fabric a mixture of soluble fatty matter—such as soda soap—clay, and starch, or gum, or glue, and coloring-matter, and then treating the fabric with chloride of calcium or other equivalent compound having the power of rendering the soluble fatty matter insoluble, substantially as described. 55

VICTOR G. BLOEDE.
